UNITED STATES PATENT OFFICE

141,895

DESIGN FOR A LIGHT TRANSMITTING MEMBER FOR A LIGHTING FIXTURE

Albert L. Arenberg, Highland Park, Ill., assignor
to Patent License Corporation, Chicago, Ill., a
corporation of Illinois

Application September 9, 1944, Serial No. 115,239

Term of patent 14 years

(Cl. D48—16)

To all whom it may concern:

Be it known that I, Albert L. Arenberg, a citizen of the United States, residing at Highland Park, in the county of Lake and State of Illinois, have invented a new, original, and ornamental Design for a Light Transmitting Member for a Lighting Fixture, of which the following is a specification, reference being had to the accompanying drawing, forming a part thereof.

In the drawing:

Fig. 1 is a perspective view of a light transmitting member for a lighting fixture, showing my new design;

Fig. 2 is a front elevational view thereof;

Fig. 3 is an end elevational view of the same; Fig. 4 is a bottom plan view of the same; and Fig. 5 is a top plan view of the same.

The light transmitting member is a downwardly facing forwardly rounded hollow panel having bottom and edge surfaces which are light diffusing. The circular sections in the bottom of the member are downwardly convex and clear.

I claim:

The ornamental design for a light transmitting member for a lighting fixture, substantially as shown and described.

ALBERT L. ARENBERG.
